UNITED STATES PATENT OFFICE

169,539

KNIFE AND SCISSORS SHARPENER

Arthur J. Folli, Chicago, Ill., assignor to Burgess Vibrocrafter, Inc., Lake Zurich, Ill., a corporation of Delaware

Application February 11, 1953, Serial No. 23,559

Term of patent 14 years

(Cl. D37—1)

To all whom it may concern:

Be it known that I, Arthur J. Folli, a citizen of the United States, residing at Chicago, in the county of Cook and State of Illinois, have invented a new, original, and ornamental Design for a Knife and Scissors Sharpener, of which the following is a specification, reference being had to the accompanying drawings, forming a part hereof.

Fig. 1 is a perspective view of the knife and scissors sharpener showing my new design;

Fig. 2 is a bottom view;

Fig. 3 is a rear view;

Fig. 4 is a side view;

Fig. 5 is a top view; and
Fig. 6 is a front view thereof.

I claim:

The ornamental design for a knife and scissors sharpener, as shown.

ARTHUR J. FOLLI.
